(57) **CLAIM**

The ornamental design for a light emitting diode, as shown and described.

DESCRIPTION

FIG. 1 is a perspective view of a light emitting diode showing the claimed design;

FIG. 2 is another perspective view thereof;

FIG. 3 is a front elevational view thereof;

FIG. 4 is a rear side elevational view thereof;

FIG. 5 is a left side elevational view thereof, the right elevational view being a mirror image of the left elevational view;

FIG. 6 is a top plan view thereof;

FIG. 7 is a bottom plan view thereof; and,

FIG. 8 is a reference view showing the visible inner structure through the light transmissible portion.

The light transmissible portion of the design is made of light transmissible material. The broken lines are directed to environment and are for illustrative purpose only; the broken lines form no part of the claimed design.
